Primary Examiner—James M. Gandy*Attorney, Agent, or Firm*—Sandler, Greenblum & Bernstein[57] **CLAIM**

The ornamental design for a tire, as shown and described.

DESCRIPTION

FIG. 1 is a perspective view of a tire, showing my new design, it being understood that the tread pattern is repeated throughout the circumference of the tire, the opposite side being substantially the same as that shown; and,

FIG. 2 is a front elevation view thereof.

FIG. 1

FIG. 2
